PENS

John P. Squier, Dallas, Tex.

Application August 21, 1952, Serial No. 305,570

7 Claims. (Cl. 346—140)

2

Figure 4 is a vertical sectional view of the reservoir taken on the line 4—4 of Figure 2,

Figure 5 is a horizontal sectional view taken on the line 5—5 of Figure 4,

5 Figure 6 is a vertical sectional view taken on the line 6—6 of Figure 4, and

Figure 7 is an enlarged fragmentary vertical side view of the pen point of the pen shown in Figures 1 and 2.

Referring now to the drawings, the reference numeral

10 designates a conventional pen having an upper arm section 11 which can be clamped to the operating shaft (not shown) of a recording instrument by means of the clamping screw 12 which draws the bifurcated upper ends 13 and 14 toward each other. An intermediate arm section 15 is adjustably secured to the lower portion of the upper arm section by screws 16 and 17 which extend through the slot 18 in the intermediate arm section into threaded bores in the upper arm section. The lower elongate arm section 19 is pivotally mounted on the intermediate section by means of the rivet 20. A micrometer screw 21 mounted on the intermediate arm section and engaging in a suitable threaded aperture in a post 22 on the upper end of the lower arm section provides for adjustment of the lower arm section about the rivet 20. The lower end of the lower arm section has a pen point 23. The pen 10 thus described is of conventional structure and it will not, therefore, be described in greater detail.

30 The ink supply system 24 includes a substantially rectangular reservoir 25 which may be secured at any position on the pen arm but is shown as attached to the lower and intermediate arm sections of the pen above the rivet 20 by means of two bands 26 and 27 which are wrapped around the reservoir and the lower and intermediate arm sections. The bands may be provided with adhesive which firmly secures the bands to the reservoir and the back of the intermediate section. The lower arm section will be free to move slightly when the micrometer screw 21 is rotated since it is not contacted by either of the bands.

45 An elongate small diameter tube 28, preferably of flexible construction, extends through an opening in the bottom 29 of the reservoir to a point substantially adjacent the upper end of the reservoir and downwardly from the reservoir along the lower arm section to a point adjacent the pen point 23. The tube 28 could be fastened exteriorly of one wall of the reservoir if desired, but the illustrated arrangement of the tube and reservoir is preferred since any liquid which may flow over the outer surfaces of the tube from the wick will return into the reservoir and will not flow over the pen. The elongate tube may be attached to the lower end of the pen arm by a band 30. The reservoir, the tube and the bands are preferably made of a light plastic.

55 A wick formed of two strands 31 and 31a extends through the tube 28. The wick is substantially longer than the tube and its upper end extends outwardly from the upper end of the tube and then downwardly to the bottom of the reservoir where the two strands are secured together by a knot. The lower end of the wick extends downwardly from the lower end of the tube and is led into the pen point 23 where it is disposed between the nibs of the pen. The lower ends of the two strands may be in the form of a continuous loop, or they may be bound together, or they may also be secured together by a knot, and disposed in the pen point. If the tube 28 becomes clogged, the wick may be drawn back and forth through the tube, the knots at the ends of the wick preventing accidental removal of the wick from the tube.

70 The internal diameter of the tube 28 is so small that the wick fits very snugly therein, permitting capillary flow, but not gravity flow, of ink from the reservoir to

This invention relates to pens and more particularly to ink supply systems for pens of the reservoir type which are adapted for use with recording instruments.

Recording instruments for recording the rate of flow of gas from wells and other varying quantities are usually provided with movable pens which trace lines on moving discs or strips of paper. Since such recording instruments are frequently placed at distant or comparatively inaccessible locations, it is necessary that the pen be supplied with ink from a reservoir of sufficient capacity to supply the pen with ink for prolonged periods of time, some times several days. The ink supply system for the pen must be dependable, for any failure of the inking system to supply ink to the pen may mean a loss of the desired recording of the variable quantity over a period of several days. Any malfunctioning of the ink supply which brings an over-supply of ink to the pen may also result in a loss of the desired recording due to blotting of the record. The ink supply system for pens of such recording instruments should be capable of adjustment to vary the rate of flow of ink to the pen, since some pens may use more ink than others due to their subject to greater or more frequent oscillations and also to variations in their structure. The differences in the physical properties of different inks also necessitate the provision of such adjustment. It is also desirable that the ink supply system be capable of being mounted directly on the pen in order that the pens of recording instruments may be equipped with such systems without any alteration or modification of the structure of the recording instrument, hence the ink supply system must be of extremely light weight.

Accordingly, it is one object of the invention to provide a new and improved ink supply system for pens of the reservoir type.

It is another object of the invention to provide a new and improved ink supply system for pens of recording instruments which is capable of supplying the pen with ink over prolonged periods of time.

It is an important object of the invention to provide an ink supply system for pens of the reservoir type having means for adjusting the rate of flow of the ink from the reservoir to the pen.

It is a further object of the invention to provide an ink supply system for pens of recording instruments which can be mounted directly on the pens.

Additional objects and advantages of the invention will be readily apparent from the reading of the following description of a device constructed in accordance with the invention and reference to the accompanying drawings thereof, wherein:

Figure 1 is a front plan view of a pen provided with the ink supply system of the invention,

Figure 2 is a side plan view of the pen shown in Figure 1,

Figure 3 is a fragmentary plan view showing the manner in which the pen is employed to trace a record on a disc of paper,

the pen point through the wick. The rate of flow of the ink is regulated by a needle valve 32 having a tapered lower end which is inserted into the upper end of the tube to press the wick strands against the walls of the tube to compress the strands and thus decrease the capillary flow of ink through the wick. The rate of capillary flow is varied by varying the vertical position of the needle valve in the upper end of the tube so that the amount of ink in the pen point will always be sufficient to form a trace 33 of the desired width on the paper chart 34 but will not be so great that the pen point is flooded and the trace blotted.

It will thus be apparent that an ink supply system has been provided which can be easily attached to any conventional pen of a recording instrument and that the ink supply system will not affect the accuracy of the instrument, since it is very light in weight, one form weighing less than one-tenth of an ounce, and since the reservoir is secured to the pen close to the point about which the pen is movable. It will also be seen that the ink supply system is provided with a reservoir 25 which can hold a large supply of ink, sufficient for operation throughout a period of many days. It is particularly to be noted that the ink is drawn by capillary action from the reservoir through a wick to the pen point and that the wick extends through and fits snugly in an elongate tube 28 so that ink may not flow by gravity down through the tube. Furthermore, it will be apparent that the needle valve 32 insertable in the upper end of the tube regulates the rate of flow of ink so that the rate of flow can be adjusted for optimum results depending on the type of ink employed, the actual physical structure of the pen and the type of recording or trace desired.

The foregoing description of the invention is explanatory only, and changes in the details of the construction illustrated may be made by those skilled in the art, within the scope of the appended claims, without departing from the spirit of the invention.

What I claim and desire to secure by Letters Patent is:

1. An ink supply system for a pen having an elongate arm provided with a pen point comprising: a reservoir adapted to be mounted on said arm; an elongate tube extending from the reservoir to a point closely adjacent but spaced from said pen point, said tube extending upwardly through the bottom of the reservoir and upwardly therein to a point adjacent the upper end of said reservoir; a wick extending through said tube and having an upper end extending outwardly from the tube and downwardly into the reservoir and a lower end extending outwardly from the tube and adapted to extend into the pen point; and a needle valve means insertable into the upper end of the tube to variably compress the wick to regulate the rate of the capillary flow of ink through the wick.

2. An ink supply system for a pen having an elongate arm provided with a pen point comprising: a reservoir adapted to be mounted on said arm; an elongate tube extending from the reservoir to a point closely adjacent but spaced from said pen point, said tube extending upwardly through the bottom of the reservoir and upwardly therein to a point adjacent the upper end of said reservoir; a wick extending through said tube and having an upper end extending outwardly from the tube and downwardly into the reservoir and a lower end extending outwardly from the tube and adapted to extend into the pen point; said wick fitting snugly in said tube whereby ink may be carried through said tube only by capillary flow through the wick; and a needle valve means insertable into the upper end of the tube adjustably compressing the wick in the tube to regulate the rate of the capillary flow of ink through the wick.

3. An ink supply system in combination with a pen having an elongate arm provided at one end with a pen point, said ink supply system comprising: a reservoir having means for removably mounting it on said arm;

5 said reservoir having a bottom provided with an aperture; an elongate tube extending upwardly through said aperture to a point adjacent the upper end of the reservoir and downwardly to a point adjacent the pen point, said tube having means adjacent its lower end for removably securing said lower end to said arm adjacent said pen point; a wick extending through said elongate tube and having an upper end extending outwardly from the upper end of the tube and then downwardly to the bottom of the reservoir and having a lower end extending outwardly from the lower end of the tube into the pen point; and a needle valve means insertable into the upper end of the tube for adjustably compressing the wick in the tube to regulate the rate of flow of ink through the wick.

10 4. An ink supply system in combination with a pen having an elongate arm provided at one end with a pen point, said ink supply system comprising: a reservoir having means for removably mounting it on said arm; said reservoir having a bottom provided with an aperture; an elongate tube extending upwardly through said aperture in sealing engagement with the bottom of said reservoir to a point adjacent the upper end of the reservoir and downwardly to a point adjacent the pen point, said tube having means adjacent its lower end for removably securing such lower end to the arm adjacent the pen point; a wick extending through said elongate tube and having an upper end extending outwardly from the upper end of the tube and then downwardly to the bottom of the reservoir and having a lower end extending outwardly from the lower end of the tube into the pen point; said wick fitting snugly in said tube whereby ink may be carried through said tube only by capillary flow through the wick; and a needle valve means insertable into the upper end of the tube for adjustably compressing the wick in the tube to regulate the rate of the capillary flow of ink through the wick.

15 5. An ink supply system for a recording instrument pen having an elongate swingable arm provided with a pen point, said ink supply system comprising: a reservoir made of thin wall light-weight rigid plastic open at its upper end and adapted to be mounted exteriorly on said arm, said reservoir having means adapted for releasably securing it on said arm; an elongate tube of light-weight flexible material extending upwardly through the bottom of said reservoir and upwardly therein to a point adjacent the upper end of said reservoir, said tube having an elongate flexible section extending below and away from the bottom of said reservoir; means on said flexible tube whereby said flexible tube is adapted to be releasably secured exteriorly to said swingable arm at a point adjacent said pen point; and a wick extending through said flexible tube and having an upper end extending outwardly from the upper end of said tube and downwardly into the reservoir and having a lower end extending outwardly from the lower end of said flexible tube and adapted to extend into the pen point; said wick fitting snugly in said tube whereby ink may be carried through said tube only by capillary flow through said wick.

20 6. An ink supply system for a recording instrument pen having an elongate arm pivotable at its upper end about a horizontal axis and provided at its lower end with a pen point, said ink supply system comprising: a thin wall plastic reservoir open at its upper end and having a closed bottom and adapted to be mounted exteriorly on said pivotable arm closer to said horizontal axis than said pen point; means on said reservoir adapted to engage said arm to secure said reservoir in place on said arm; an elongate flexible tube extending upwardly through the bottom of said reservoir and upwardly therein to a point adjacent the upper end of said reservoir and having an elongate flexible depending portion extending downwardly below the bottom of said reservoir a substantial distance, the lower end of said flexible tube being adapted to

be secured exteriorly to said pivotal arm adjacent the pen point; securing means on said lower portion of said flexible tube adapted to engage the swingable arm to secure said lower end of said tube to said swingable arm adjacent said pen point; and a wick extending through said tube and having an upper end extending outwardly from the upper end of the tube and then downwardly into the reservoir and having a lower end extending outwardly from the lower end of the flexible tube and adapted to extend into the pen point, said wick fitting snugly in said tube whereby ink may be carried through said tube only by capillary flow through said wick.

7. An ink supply system for a recording instrument pen having an elongate arm pivotal at its upper end about a horizontal axis and provided at its lower end with a pen point, said ink supply system comprising: a thin wall rigid plastic reservoir open at its upper end and having a closed bottom and adapted to be mounted exteriorly on said pivotal arm closer to said horizontal axis than said pen point; means on said reservoir adapted to engage 20 said arm to secure said reservoir in place on said arm; an elongate flexible tube extending upwardly through the bottom of said reservoir and upwardly therein to a point adjacent the upper end of said reservoir and having an elongate flexible depending portion extending downwardly 25 below the bottom of said reservoir a substantial distance,

the lower end of said flexible tube being adapted to be secured exteriorly to said pivotal arm adjacent the pen point; securing means on said lower portion of said flexible tube adapted to engage the swingable arm to secure 10 said lower end of said tube to said swingable arm adjacent said pen point; a wick extending through said tube and having an upper end extending upwardly outwardly from the upper end of the tube and then downwardly into the reservoir and having a lower end extending outwardly from the lower end of the flexible tube and adapted to extend into the pen point, said wick fitting snugly in said tube whereby ink may be carried through said tube only by capillary flow through said wick; and needle valve 15 means slidably adjustable in the upper end of the tube to variably compress the wick to regulate the rate of capillary flow of ink through the wick.
